DESCRIPTION

U.S. PATENT DOCUMENTS

FIG. 1 is a front, right, and top perspective view of a wine glass holder, showing my design.

D127,900 S * 6/1941 Block D6/699
D198,098 S * 4/1964 Kaneko D7/701
4,947,991 A * 8/1990 Snell A47B 13/16
206/427

FIG. 2 is a rear, left, and bottom perspective view thereof.

D505,841 S * 6/2005 Fiedeler D7/637

FIG. 3 is a front elevation view thereof.

D786,029 S * 5/2017 Pannell D7/708

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the wine glass holder that form no part of the claimed design.
